UNITED STATES PATENT OFFICE.

THOMAS CARLESS, OF HALEDON, NEW JERSEY.

SNOW-REMOVING MACHINE.

Application filed August 19, 1926. Serial No. 130,193.

The principal object of this invention is to provide a rotary snow plow which may be used interchangeably for removing snow from country roads or other ways which are flanked by open spaces into which the snow may be delivered at a distance from the machine or for removing snow from streets or other ways which are flanked by side-walks and buildings and therefore require the snow to be deposited in the gutters or along the margins of the side-walks. Another principal object is to provide a dirigible snow plow machine of the kind in which the actual plow is arranged ahead of a vehicle carrying it which shall be so constructed that the plow will not be obstructed and the apparatus racked and perhaps damaged due to the presence of sudden rises or falls in the road or street, as transverse humps or depressions.

In the drawings,

Fig. 1 is a side elevation of the improved machine;

Fig. 2 is a plan;

Fig. 3 is a transverse section on line 3—3, Fig. 1;

Fig. 4 shows a detail of Fig. 3;

Fig. 5 is a front elevation;

Fig. 6 is a section on line 6—6, Fig. 5;

Fig. 7 is a plan of the fan casing detached from the remainder of the plow structure; and

Fig. 8 is a fragmentary plan of the bottom portion of said casing.

1 is a chassis mounted on four wheels 2, the front wheels being adapted to be turned for steering by the steering wheel or equivalent. Whether or not the vehicle thus formed is self-propelled is not material: in the present example it is shown ahead of and coupled at 4 with an automobile, as a truck 5, which drives said vehicle, which is then steered by the means 3.

Without as yet adverting to details I note that a plow, comprising the plow proper generally denoted by 6 and its shank generally denoted by 7, has its shank pivoted to the chassis so that the plow is capable of up and down movement with respect to the chassis, and that, being thus in part supported by the chassis, it is also supported ahead of the vehicle by runners 8 (here directly underlying and supporting the plow proper) which are elongated longitudinally of the vehicle and travel on the ground, the object in elongating the runners being to insure their sliding or running over sudden rises and falls in the road

without catching and without causing undue up and down motion of the plow. One important feature of my invention consists in forming said structure with a relatively long shank pivoted back of the front wheels while the plow proper is close to the front wheels and its front-to-rear dimension is a relatively small part of the front-to-rear dimension of the machine, so that the machine has a very short turning-radius. Preferably the shank is so long as to reach to and be pivoted at the rear of the vehicle; but in that case I prefer to provide means on the vehicle to engage said structure at its forward portion and so guide it in its up and down movements, as will appear.

This snow removing machine is also intended for removing snow from more or less smooth roads; but on such roads, or wherever else the machine would have to travel in going to and from them, there might occasionally be deep places which if the runners 8 encountered would put an undue strain on the runners and in fact the whole plow structure; hence, it will be noted that when such deep places are encountered the plow frame 7 will ride upon the main frame 1, until the deep place is passed.

The so-called shank of the plow is a rectangular frame which overlies the chassis; there may be guides 11 to hold the frame against side-lash in its up and down movement around the pivotal connections between it and the chassis afforded by the hinges 10. The plow proper is preferably of the rotary type and includes a fan or rotary ejector 12, whose rearwardly projecting shaft 13 is journaled in the frame in suitable bearings 14, and a fan casing rigidly secured to the frame.

Any rotary fan such as is used in railroad snowplows may be employed, so the details thereof are not material in the present case except that it is preferable that the fan be capable of rotating in either direction, wherefore I utilize a fan comprising the radial funnels 12^a open longitudinally and at their outer ends and each equipped at each side of its longitudinal opening with a feathering blade 12^b, the adjoining blades for each two funnels being pivotally coupled together by links 12^c; when the fan is rotating in that direction in which the hinged edges of one set of blades are leading such blades will trail and be idle whereas the other set will then be the operating blades. The fan shaft 13 is operatively connected with the shaft 16 of a

motor 17 (as an internal combustion or electric motor) through a reversing-gear comprising bevel gears 13^a and 16^a fixed on the two shafts and a pair of bevel gears 18 revoluble as a unit on the shaft 18^a and also slideable thereon, by means of the lever 18^b, so as to place one of them in and the other out of mesh with the gears 13^a, 16^a. Said motor is mounted on the plow frame 7, and one object in extending the frame rearwardly is thereby to reduce to the minimum the up and down motion which the motor will undergo.

The fan casing includes the shell 19 closed at the back and provided with a front flaring mouth or intake 20 and having that wall which directly surrounds the fan mainly cylindrical but developed into a peak 19^a at the top, with an opening 19^b in each side thereof; these openings are controlled by valves or doors 21 here arranged to slide in vertical ways 21^a and conveniently connected by a flexible connection 21^b extending over a pulley 21^c so that when one valve is lowered to expose its opening the other rises and closes its opening. The fan casing may be braced by the braces 22 connecting it with the frame 7.

It is not material what form or construction the runners take so that they are elongated as stated. But I here show them as simple skids. Preferably they have their forward ends upturned, as at 8^a, and sharpened, as at 8^b, so as both to avoid their catching on fixed obstacles and insure their cutting their way through hard snow or ice. It is necessary to fix these skids to the casing in some substantial way which will avoid straining the latter, and it is also desirable to provide for their removal. Hence the lower portion of the flaring mouth 20 of the casing has rigidly secured to its under side a casting 23 which is transversely straight and which may have an upstanding flange 23^a which may be rigidly secured to the rear wall of the casing; and the under side of this casting has front-to-rear extending dove-tailed grooves 23^b adapted to receive dove-tailed ribs 8^c on the skids, which also have stop lugs 8^d to bear against the front edges of the casting 23 when the skids are fitted to these grooves.

As so far described the machine is adapted for removal of snow from country roads or other ways flanked by spaces into which the snow can be discharged at a distance from the machine. In order to adapt the machine for use in removing snow from town or city streets where the ways of this class do not permit deposit of the snow at a distance from the machine I provide the deflectors 24. Each of these is an inverted curved trough-like structure arranged to overlie one of the openings 19^b with its side edges resting on the casing when in operative position, its delivery end discharging downwardly and so that

the discharged mass will meet the ground close to the machine, as in the gutter or along the curb of the street. These deflectors are removable from the openings, so as to convert the machine to road use, preferably by hinging them along one side of each to the casing, as at 24^a; one of them is shown swung back on its hinges and resting on a bracket 24^b on the casing, or in idle position, in Fig. 6.

When the machine is travelling but not operating to remove snow it is desirable to elevate the plow to an idle position. For this purpose I have provided the elevating means shown in Figs. 3 and 4 where 25 is a transverse manually rotatable shaft journaled in the chassis and carrying bevel gears 26 meshing with bevel gears 27 formed on or affixed to nuts 28 journaled in the chassis and receiving threaded stems 29 that are upwardly engageable with projections 30 of frame 7 when the shaft and hence the nuts are turned to elevate said stems.

An important feature of my invention is that the actual deflecting wall of the deflector or deflecting hood, being the curved or top wall thereof in Fig. 5, slopes gradually downwardly from a point above the corresponding opening 19^b. Of course the delivery from the casing takes place through that one of the two openings which is in a trajectory from the ejector according to its direction of rotation (for example, the right-hand opening in Fig. 5 if the ejector rotates clockwise), and this form of deflector accomplishes the desired placement of the snow close beside the machine without its packing and clogging the deflector.

The transversely straight basal or shoveling portion 23 of the plow casing acts to cut through mounded and more or less hardened snow masses, levelling them off, an operation which is facilitated by the skids which, being sharpened, previously cut such masses into sections.

Having thus fully described my invention, what I claim and desire to secure by Letters Patent is:

1. A machine of the class described including a portable supporting means, an ejector rotatable on a fore and aft axis therein, a casing open at the front and housing the ejector and having a lateral delivery opening, and an inverted trough-like deflector exterior of the casing including a deflecting wall sloping gradually downwardly from approximately the top of said opening, said deflector having its lateral edges normally resting on the casing.

2. A machine of the class described including a portable supporting means, an ejector rotatable on a fore and aft axis therein, a casing open at the front and housing the ejector and having a lateral delivery opening, and an inverted trough-like deflector exterior of the casing including a deflecting

wall sloping gradually downwardly from approximately the top of said opening, said deflector having its lateral edges normally resting on the casing and being shiftable on the 5 casing clear of said opening.

3. A machine of the class described including a portable supporting means, an ejector rotatable on a fore and aft axis therein, a 10 casing open at the front and housing the ejector and having a lateral delivery opening, and a deflector exterior of the casing including a deflecting wall sloping gradually downwardly from a point above said opening, said deflector being hinged on the casing 15 on an axis transverse to the first-named axis and thereby shiftable clear of said opening.

4. A plowing machine comprising a dirigible vehicle having front and rear wheels, a 20 structure pivotally and freely movable up and down with respect to the vehicle and including, with a portion ahead of the vehicle having runner means to travel on the ground, a relatively long shank rigidly projecting 25 rearward from said portion and pivoted to the vehicle on a transverse substantially horizontal axis at the rear part of the vehicle, said vehicle having forward means to guide said structure up and down, and ejector means 30 movable in said structure ahead of the ve-

hicle, said portion and runner means together forming a plow proper and such plow proper being close to the front wheels of the vehicle and having its front-to-rear dimension a relatively small extent of the front-to-rear dimension of the machine. 35

5. A plowing machine comprising a dirigible vehicle having front and rear wheels, a structure pivotally and freely movable up and down with respect to the vehicle and including, with an upright casing ahead of the vehicle having runner means to travel on the ground, a relatively long shank rigidly projecting rearwardly from the casing and pivoted to the vehicle on a transverse substantially horizontal axis rearward of the front wheels, said casing having a front receiving opening and a discharge outlet, a shaft extending longitudinally of and journaled in the shank, a rotary ejector carried 50 by the shaft within the casing, and means on the shank to rotate the shaft, said casing and runner means forming a plow proper and such plow proper being close to the front wheels of the vehicle and having its front-to-rear dimension a relatively small part of the front-to-rear dimension of the machine. 55

In testimony whereof I affix my signature.

THOMAS CARLESS.
